UNITED STATES PATENT OFFICE.

EDWIN C. WASHBURN, OF ENGLEWOOD, NEW JERSEY.

BRAKE BEAM.

Application filed June 18, 1920. Serial No. 389,996.

To all whom it may concern:

Be it known that I, EDWIN C. WASHBURN, a citizen of the United States, residing at Englewood, in the county of Bergen and State of New Jersey, have invented certain new and useful Improvements in Brake Beams; and I do hereby declare the following to be a full, clear, and exact description of the invention, such as will enable others skilled in the art to which it appertains to make and use the same.

My present invention provides an improved brake beam and includes also an improved process of making the same. A novel feature of the invention consists in first independently forming the compression and tension members of the beam, in connecting a swiveled strut to the intermediate portions of these members by casting coupling brackets onto the same, and connecting the ends of said compression and tension members by casting hubs thereon.

The invention is illustrated in the accompanying drawings wherein like characters indicate like parts throughout the several views.

Referring to the drawings:

Fig. 1 shows the improved brake beam and a connected brake shoe head, partly in elevation and partly in vertical section, some parts being broken away;

Fig. 2 is an elevation of the parts shown in Fig. 1, some parts being sectioned;

Fig. 3 is an end elevation of the parts shown in Figs. 1 and 2;

Fig. 4 is a perspective view showing one end of the beam;

Fig. 5 is a perspective view of the brake shoe head;

Fig. 6 is a perspective view showing one end of the compression member of the beam before it has been completely formed; and

Fig. 7 is a view corresponding to Fig. 6, but showing the completely formed end of said compression member.

The numerals 8 and 9 indicate, respectively, the compression and tension members of the beam, the former being a rolled channel, and the latter being a heavy rod.

Both of said members are, of course, independently cut to proper length and the tension member 9 is bent to proper form.

The numeral 10 indicates a swiveled strut which is formed independently of the compression and tension members, preferably

by casting, is provided with a rectangular passage 11 and with headed swiveled studs 12 at its ends. The strut 10 is provided with transverse bolt holes 13 through which a bolt may be passed to pivotally connect the brake lever, not shown, thereto, in the customary way.

In the process of making this beam, the properly formed compression and tension members 8 and 9 are placed in proper relative positions, and the strut 10 is properly positioned between the same; and then conical hubs 14 are cast directly against and onto the ends of the said members 8 and 9, and coupling blocks 15 and 16 are, respectively, cast around the intermediate portion of the compression member 8 and onto the adjacent headed stud 12, and around the intermediate portion of the tension member 9 and onto the adjacent headed stud 12. The hubs 14 and coupling blocks 15 and 16 will, of course, be formed by the use of suitable molds placed around the members. To prevent the blocks 15 and 16 from being cast fast to the headed studs 12, the latter are coated or painted with sand or a solution containing sand, so that when the metal has cooled, the strut 10 will be swiveled, that is, capable of angular oscillation on its longitudinal axis.

To insure a good connection between the ends of the compression members or channels 8 and the hubs 14, the webs of said members 8, at their ends, are cut away to form V-shaped notches 8^a shown in Fig. 6, and then these end portions are pressed together, as shown in Fig. 7, so that the ends of the members 8 are tapered.

The tension members or rod 9 are threaded, project beyond the hubs 14, and are provided with nuts 17.

The numeral 18 indicates one of the brake beam heads, the same being provided with tapered conical sockets 19 that fit the hubs 14. The threaded ends of the compression member or rod 9 project through the outer walls of the heads 18 and, when the nuts 17 are tightened against the same, the said heads will be rigidly secured to said hubs. The said heads 18, however, are capable of rotational adjustments about hubs 14 so as to bring the shoes into proper contact with the wheels.

The swiveled strut 10 is, as is obvious, capable of oscillation, either toward the

right or toward the left, so as to set the same for use at either end of the truck, or for levers that incline in either direction.

The brake beam construction, as described, 5 may be made at comparatively small cost, is very strong and durable, and generally efficient for the purposes had in view, and for a given weight, has a maximum of strength. It may be made chiefly from 10 commercial iron and the foundry work is reduced to a minimum.

What I claim is:

1. A brake beam having independently formed compression and tension members 15 rigidly and permanently united by metal cast around the same.

2. A brake beam having independently formed compression and tension members rigidly and permanently united by metal 20 cast around the same, both at the intermediate and end portions of said members.

3. A brake beam comprising compression and tension members and a strut formed independently thereof, said compression and 25 tension members being connected at their ends by hubs cast fast thereto, and said strut being connected to the intermediate portions of said compression and tension members with freedom for swiveled movements, by 30 metal blocks cast loosely to the ends thereof and cast fast to said compression and tension members.

4. A brake beam having independently formed compression and tension members 35 rigidly and permanently united by metal cast fast thereto, both at the intermediate and end portions of said members, said tension member having threaded nut-equipped ends that project beyond the ends of the 40 compression member and are adapted to secure brake shoe heads to the ends of said beam.

5. A brake beam comprising compression and tension members and a strut formed independently thereof, said compression and 45 tension members being connected at their ends by hubs cast fast thereto, and said strut being connected to the intermediate portions of said compression and tension members 50 with freedom for swiveled movements, by metal blocks cast loosely to the ends thereof and cast fast to said compression and tension members, said tension members having threaded nut-equipped ends that project beyond 55 said hubs and are adapted to secure brake shoe heads to said hub.

6. A brake beam comprising compression and tension members and a strut formed independently thereof, said compression and 60 tension members being connected at their ends by hubs cast fast thereto, and said strut being connected to the intermediate portions of said compression and tension members with freedom for swiveled movements, by metal blocks cast loosely to the

ends thereof and cast fast to said compression and tension members, said tension members having threaded nut-equipped ends that project beyond said hubs and are adapted to secure brake shoe heads to said hub, the 70 said hubs and seats therefor in said heads being tapered, and said heads being rotatively adjustable on said hubs.

7. The process of making brake beams which consists, first in independently forming compression and tension members, and in thereafter rigidly connecting said members by metal cast around the ends of the same and to the intermediate portions thereof. 75

8. The process of making brake beams which consists in independently forming compression and tension members and a strut, and connecting the ends of said compression and tension members by casting 80 hubs fast thereto, and in connecting the ends of said strut to the intermediate portions of said compression and tension members with freedom for swiveled movements, by casting 85 blocks fast to said compression and tension members and loosely against the ends of said strut.

9. A strut structure formed of a plurality of relatively movable members cast together.

10. A brake beam having independently 95 formed compression and tension members rigidly and permanently united by metal cast around the same, said tension member having threaded nut-equipped ends that project beyond the ends of the compression 100 member and are adapted to secure brake shoe heads to the ends of said beam.

11. The process of making brake beams which consists in independently forming compression and tension members and thereafter rigidly connecting said members by metal cast around the portions to be joined. 105

12. A truss having its compression and tension members held apart by a strut cast to each member.

13. A truss having its compression and tension members held apart by a strut comprising three parts, one of which is cast to the compression and one to the tension member. 115

14. The structure set forth in claim 13, the third part of said strut being arranged to turn between the other two.

15. A truss having a three-part cast strut having a central portion, said central portion being arranged for movement relative to the other portions. 120

16. A truss having a strut having center and end portions, said center portion being cast to one end portion.

17. The structure set forth in claim 16, said center portion of the strut being arranged for rotary movement.

18. A truss having a strut comprising a center portion having heads formed thereon 130

and an end portion cast about said head, said center portion having rotary movement.

19. A truss comprising a strut having a central opening therein and having metal 5 cast about its ends for connection with the truss members.

20. A brake beam having in combination, 10 a compression member, a tension member, said members being rigidly and permanently united at their end portions, a member cast to said compression member at the center

thereof, and extending toward the tension member, and a member cast to said tension member at the center thereof and extending toward said compression member, 15 said last mentioned members being cast about a member extending therebetween and rotatably mounted therein.

In testimony whereof I affix my signature.

EDWIN C. WASHBURN.
